SHIELDED AIRCRAFT SPARK PLUG

Hector Rabezzana and Alexander J. Battey, Flint,
Mich., assignors to General Motors Corporation,
Detroit, Mich., a corporation of Delaware

Application January 5, 1940, Serial No. 312,476

2 Claims. (Cl. 123—169)

Our invention relates to spark plugs designed to ignite the combustible mixture supplied to and burned within the working cylinder of an internal combustion engine, and particularly to spark plugs for use in shielded ignition systems wherein the conductor or lead wire through which current is supplied to the insulated electrode of the plug is enclosed in a metallic envelope which, in turn, is connected to the metallic shell or casing of the plug. The plug itself or, more strictly speaking, the casing thereof being screwed into a threaded opening in an engine cylinder, it follows that the envelope enclosing the supply lead is grounded to the engine structure through the metallic shell or casing of the plug; thus preventing the high tension oscillating current in the supply lead from interfering with the operation of radio receiving apparatus located adjacent the engine equipped with an ignition system having such shielded leads and spark plugs.

Our invention is concerned with the spark plug itself, and not with the system as a whole whereby shielding of the ignition leads is accomplished, and the object thereof is to provide a better heat conducting path from the central insulated electrode to the shell or casing of the plug than has heretofore been obtained; so the plug will operate cooler, and will be less liable to injury due to overheating, than has been the case in spark plugs such as have heretofore been used. To that end our invention consists in providing the usual shell or casing of the plug with an upwardly extending shield portion designed to be electrically connected with the metallic envelope enclosing the supply lead, in certain relationships between the shield portion and the central insulated electrode of the plug, and various other features hereinafter described and claimed.

Our invention includes a tubular lining member of plastic insulating material molded in place within the upwardly extending shield portion of the shell or casing of the plug, and in intimate contact with the interior thereof and with the exterior of the upper portion of the insulating member of the plug, whereby a better heat conducting path and one of minimum resistance to the flow of heat from the central electrode and insulating member to the shell or casing, is secured.

In the drawing accompanying and forming a part of this specification:

Figure 1 is a view showing our improved spark plug partly in elevation, and partly in section upon a vertical central plane; the plug being shown about full size.

Figure 2 is a view similar to Figure 1 showing a supply cable secured to the plug so as to supply current thereto, and the metallic sheath of which cable is grounded to the shell or casing of the plug.

Figure 3 is a view illustrating one step of the method whereby a tubular lining member is molded in place within the shell or casing of the plug, the plug being shown about twice the size 10 it is shown in Figures 1 and 2.

Figure 4 is a view similar to Figure 3 but showing a later step of the method whereby the tubular lining member of our spark plug is molded in place within the exterior shell or casing thereof.

Referring now to the drawing, the tubular metallic shell or casing of our improved spark plug is threaded at its lower end 5 to screw into a threaded opening in an engine cylinder and comprises a lower portion 6 within which the enlarged central portion of the insulating member 15 7 of the plug is secured, and an upper tubular shield portion 8 shown as integral with the lower portion, but which may be separate therefrom and secured to the lower portion in any way so as to form a unitary shell or casing for the plug.

The insulating member is supported by an internal ledge 9 within the lower portion of the shell, and the upper end thereof extends into the upper shield portion of the shell and is smaller 20 in diameter than said shield portion, so as to provide an annular space between the two. The insulating member is held in place within the lower portion 6 of the shell or casing by an externally threaded annular sleeve 10 in engagement with an internally threaded seat within the shield portion 8, as shown, and through which sleeve the upper end of said insulating member extends; an annular holding member being interposed between the sleeve and an annular 25 shoulder 11 upon the insulating member. This holding member is shown as in the form of a C-shaped gasket 12 made of spring steel so that when the sleeve 10 is screwed downward the insulating member is forced against the ledge 9 30 by pressure transmitted through the gasket 12 and shoulder 11; the insulating member being thus permanently held in place within the lower portion 6 of the shell within which it is housed independently of the tubular lining member to 35 be next described.

After the insulating member 7 has been assembled within the shell or casing and secured in place therein by the annular sleeve 10 and C-shaped gasket 12, as hereinbefore explained, a tubular lining member 13 of plastic material is

molded in place within the upwardly extending shield portion 8 of the shell; said member being molded in place under pressure so that intimate contact is secured between the periphery thereof and the interior of the shield portion 8, and between said lining member and the exterior of the upwardly extending portion of the insulating member. A portion of the material of the lining extends over the upper end of the insulating member and into contact with the upper end of the insulated electrode 14 as indicated by the numeral 15. The intimate contacts thus secured provide a heat conducting path of minimum resistance to heat flow from the central electrode 14 and the upper portion of the insulating member to and into the lining member 13, and from said member to the shield portion 8 of the shell; from which the heat is dissipated into the surrounding atmosphere and a plug which operates at a lower temperature than heretofore is secured.

The numeral 16 designates a metallic voltage dispersing member, preferably cup-shaped in form as shown, in contact with the upper end of the central electrode of the plug and the periphery of which is embedded in the inner surface of the tubular lining member 13; the purpose of this member being to distribute the voltage present at the upper end of said electrode through an area equal to the circumference of said member times its height. The voltage at said upper end being thus dispersed (as distinguished from being concentrated at one or more points of limited area), it follows that the wall of the lining member 13 is less likely to be injured, as by a short circuit between the upper end of the central electrode and the grounded shell portion 8, or otherwise, than is the case when such voltage is or may be concentrated at points of limited area upon the inner surface of said lining member.

In making a spark plug in accordance with our invention the insulating member 7 and central electrode are assembled within the shell or casing and secured in place by the annular sleeve 10 and holding member 12, as hereinbefore appears, and plastic material to form the tubular lining member 13 is put into the upper shield portion 8 of the shell, as indicated by the numeral 17 in Figure 3. The plug is then placed upon a suitable annular anvil 18 and held in contact therewith by an annular holding member 19, the two being maintained in alignment by a die block 20; and a plunger 21 which is guided by holding member 19 as shown is forced into the shield part 8 thus displacing the plastic material 17 and causing it to fill the shield portion of the shell or casing, as shown in Figure 4; with the result that intimate contact is secured between said plastic material and the interior of the shell, and with the exterior of the upwardly extending part of the insulating member. A cup-shaped member 22 is put upon the extremity of the plunger 21, see Figure 3, before it is forced into the shield part 8; and the bottom wall of this member is pierced by the sharpened extremity of the central electrode 14 as the plunger approaches the end of its downward movement, see Figure 4, thus establishing a current conducting

joint between the central electrode and the voltage dispersing member 16, which member becomes embedded in the inner surface of the tubular lining member at the end of the downward movement of the plunger and is left in place, see Figure 1, as the plunger is withdrawn after the completion of the molding operation.

The tubular lining member 13 is preferably made of Bakelite in which case the plastic material 17 placed in the shield portion 8 of the shell consists of a suitable amorphous and uncured material or composition from which a finished Bakelite article (the tubular lining member herein) may be formed; and the plunger 21 is depressed to accomplish molding of the member 13 in situ, the same as heretofore explained. The material used is commonly heated to a temperature of around 100 to 150 degrees centigrade before being supplied to the plug casing, and the plug with the lining molded in place is commonly kept at a temperature of around 150 degrees centigrade for around one minute after the molding operation to permit the Bakelite material to coalesce and form an integral and solid lining member.

Having thus described and explained our invention, we claim and desire to secure by Letters Patent:

1. A spark plug comprising a hollow metallic shell or casing threaded at its lower end to screw into an opening in an engine cylinder and having a lower portion for housing an insulating member, and having also an upper shield portion; an insulating member located within the lower and extending into the upper shield portion of said shell, and the upper end of which insulating member is smaller in diameter than the interior of said shield portion so as to provide an annular space between the two; means for securing said insulating member in place within the lower portion of said shell; and a tubular lining member of plastic material molded in place within said annular space and in intimate contact with the interior of said shield portion and with the exterior of the upper end of said insulating member, and which lining extends above the upper end of said insulating member.

2. In a spark plug of the class described, a hollow metallic shell or casing threaded at its lower end to screw into an opening in an engine cylinder and having an internal supporting ledge, an internally threaded seat, and a shield portion extending above said seat; an insulating member within said shell and supported by said ledge, and which member extends above said threaded seat and into said shield portion and has an annular shoulder; an externally threaded annular sleeve in engagement with said threaded seat and through which the upper end of said insulating member extends; an annular holding member between said sleeve and the shoulder aforesaid of said insulating member; and a tubular lining member of plastic material molded in place within said shell and in intimate contact with the interior of the shield portion thereof and with the exterior of the upwardly extending portion of said insulating member.

HECTOR RABEZZANA.
